UNITED STATES PATENT OFFICE.

JULIUS DINHOFER, OF NEW YORK, N. Y.

CONNECTION DEVICE FOR WATCHES.

Application filed April 12, 1928. Serial No. 269,386.

This invention relates to a device intended to connect a wrist strap or ribbon to a wrist watch or other type of watch and has for its object to provide a device which shall be of 5 extremely simple and sturdy construction; which shall be composed of few parts; and which shall be entirely reliable in operation as well as ornamental in appearance.

With these objects and such other objects 10 as may hereinafter appear, in view, I have devised the particular arrangement of parts hereinafter set forth and more particularly pointed out in the claims appended hereto.

Reference is to be had to the accompanying 15 drawing, forming a part hereof in which

Figure 1 is a plan view of my improved 20 connection device with parts of a watch being shown in section to illustrate the manner in which the device is attached to a watch;

Figure 2 is a sectional view on the line 2—2 25 of Figure 1, looking in the direction of the arrows;

Figure 3 is a sectional view on the line 3—3 30 of Figure 1, looking in the direction of the arrows;

Figure 4 is a perspective view of the connection member in its open position; and

Figure 5 is a plan view of the connection 35 device in its open position with the locking member moved from between the connecting arms.

Throughout the various views of the drawings, similar reference characters designate 40 similar parts.

In the embodiment of my invention disclosed in the accompanying drawing, 1 indicates a part of a watch case of the wrist watch type. This type of watch is usually provided with a pair of spaced outstanding 45 lugs 2 which afford an attachment to a connection member usually employed on the wrist strap or band. These lugs 2 are each provided with an aperture 3 extending through them.

At 4 is shown a part of the connection member which is in the form of a three-sided frame having a pair of spaced resilient arms 6 which are integrally connected at one of their ends by a cross-bar 5. At their opposite end, each of the arms 6 is provided with a laterally extending or off-set projecting portion 7. These two portions are adapted to project into the openings 3 in the lugs 2 on the watch case and so connect the connection 50 member to said case. The frame 4 just described is preferably made of a single piece of

resilient or spring wire and the arms 6 are preferably bent inwardly towards one another and when in their normal position, or position of rest, the distance between the outer ends of the projecting parts 7 is preferably less than the distance between the two openings 3 in the case.

Through this arrangement, the connection member may be readily attached to the watch 60 by placing the frame 3 so that the off-set ends 7 are aligned with their adjacent openings 3, whereupon the arms 6 are spread apart by a suitable distention member to cause the ends 7 to be projected into the openings 3 and held therein.

The distention member just mentioned is shown at 8 and the same consists of a plate-like section of sheet metal having one of its ends rolled at 9 about the cross-bar 5 on the frame to provide a bearing for the member 8. At its opposite end, the plate 8 is folded as 70 at 10 to provide an under-surface 13 which extends backward to the bearing 9.

Adjacent to the fold 10, the opposite edges 75 of the member 8 are inwardly notched or recessed as at 11 and 12. These recesses are adapted to snap into engagement with the arms 6 and hold the member 8 so that it occupies a position between the arms 6, holding 80 said arms distended apart with their ends 7 projected into the apertures 3 in the watch case as is clearly shown in Figure 1.

From the foregoing, the manner in which 85 my improved connection member operates will be clearly understood. The device in its open position is shown in Figures 4 and 5. At this time, the ends 7 on the frame 4 are spaced apart a distance less than the distance between the apertures 3 so that the connection device may be readily placed in position between these apertures with the ends 7 on the frame aligned therewith. By moving the member 8 so that it is positioned between the arms 6, the recesses or notches 11 and 12 will snap or click into engagement with the arms 6 as clearly shown in Figure 3, causing said arms to be spread apart and the ends 7 moved into the apertures 3 and retained therein as long as the distention member 8 occupies its 90 position between the arms 6.

To free the device from the watch case, it is merely necessary to swing the distention member 8 about its pivot so that it moves outward from between the arms 6 whereupon 95 said arms 6, through their natural resiliency 100 will spring inward or toward one another.

as indicated by the arrows 15 in Figure 5.

The wrist strap or ribbon 16 shown in dotted lines in Figure 2 is attached to the connection member by passing or looping 5 about the distention member 8.

While I have mentioned my invention as being applicable to watches of the wrist watch type, it is obvious that it may be used 10 in connection with other types of watches, wherein it is desired to connect a ribbon or strap to a watch that is provided with a pair 15 of spaced openings to receive a connection member.

Having described one embodiment of my 15 invention, it is obvious that the same is not to be restricted thereto, but is broad enough to cover all structures coming within the scope of the annexed claims.

What I claim is:

- 20 1. An article of the class described comprising a frame composed of a pair of spaced resilient arms having their ends terminating in laterally extending parts adapted to enter openings in a watch case, a cross piece connecting the arms, and an extension member pivoted on the cross piece and adapted to spread the arms apart when the same is moved to a position between said arms.
- 25 2. An article of the class described comprising a frame composed of a pair of spaced resilient arms connected by a cross piece, the ends of said arms opposite to the cross

piece extending outwardly, a plate member pivoted on the cross piece and adapted to spread the arms apart when the same is 35 moved to a position between said arms, and notches on the plate adapted to snap into engagement with the arms.

3. An article of the class described comprising a wire frame having a pair of spaced 40 resilient arms terminating in outwardly extending portions adapted to enter spaced openings in a watch case, said arms being normally spaced apart for a distance less than that between the openings in the watch case, a plate member pivoted on the frame capable of being moved to occupy a position between the arms, and notches in the opposite edges of the plate adapted to snap into engagement with the arms. 50

4. An article of the class described comprising a frame having a pair of spaced arms provided with ends adapted to enter openings in a watch case, means for spreading said arms apart comprising a member 55 movably mounted on the frame and capable of movement to a position between the arms, and means on said member for engaging with the arms to hold said arms in their distended position while said member is located in between the arms. 60

Signed at the city, county and State of New York, this 10th day of April, 1928.

JULIUS DINHOFER.
